UNITED STATES PATENT OFFICE.

IRAD HAWLEY, OF EAST ORANGE, NEW JERSEY.

TOOTH-POWDER BOX.

SPECIFICATION forming part of Letters Patent No. 635,135, dated October 17, 1899.

Application filed July 10, 1899. Serial No. 723,262. (No model.)

To all whom it may concern:

Be it known that I, IRAD HAWLEY, a citizen of the United States, residing at East Orange, in the county of Essex and State of New Jersey, have invented an Improvement in Tooth-Powder Boxes, of which the following is a specification.

The object of my invention is to be able to deliver lengthwise upon the body of the bristles of a tooth-brush a quantity of tooth-powder that is just sufficient for one application and at the same time to prevent the escape of any of the main body of tooth-powder from the receptacle.

15 In carrying out my invention I provide the tooth-powder receptacle or box with a cylindrical top closed at both ends and open at the union of the cylindrical top with the tooth-powder receptacle. I also provide a narrow axial mortise in one side of the cylindrical top and a transverse mortise in the other side of said top. The cylindrical top has a hollow plug fitting within it, in which there is a recess, made longitudinally of the plug, of a size adapted to hold sufficient tooth-powder for one application. This recess normally occupies a position over the opening between the cylindrical top and the tooth-powder receptacle, so that when the receptacle or box is overturned the recess is filled with tooth-powder, and I provide a projecting stem and head moving in the transverse mortise for turning the hollow plug about a quarter of a revolution, so as to bring the recess filled with tooth-powder opposite the axial mortise in the cylindrical top, so that when the receptacle or box is turned to one side the powder will be delivered upon the bristles of the tooth-brush in line with the row of bristles.

40 To insure the delivery of the tooth-powder from the receptacle in the hollow plug, I prefer to employ a plate of metal normally lying adjacent to the bottom of the recess and to continue the stem employed to turn the plug through the plug and connect the same to said plate and to place around said stem a helical spring, whose action is to keep the plate in place against the bottom of the recess. When the stem is moved endwise, the said plate is 45 moved toward the mouth of the recess and the powder is forced out by the action of the plate.

In the drawings, Figures 1 and 2 are elevations from opposite sides. Fig. 3 is an end view, and Fig. 4 a cross-section at the upper 55 end of exaggerated size.

The tooth-powder receptacle or box *a* is preferably rectangular in a cross-section. The upper end of the same is contracted and the cylindrical top *b* with closed ends is connected 60 to the contracted end of the receptacle or box, there being a long narrow internal opening where the cylindrical top and the receptacle or box are joined. The cylindrical top *b* is provided at one side with a narrow axial mortise 2 and at the other side with a transverse mortise 3. The plug *c*, fitting within the cylindrical top *b*, is preferably hollow and the ends may be closed, and the plug is provided with a recess *c'*, whose outlines conform to 70 the axial mortise 2 in the cylindrical top. The normal position of this recess is at the opening between the cylindrical top and the powder receptacle or box, so that when the same is overturned the said recess is filled 75 with powder, and the plug fits the cylindrical top sufficiently tight to prevent any of the main body of tooth-powder accidentally escaping through the mortises 2 or 3.

I employ a head *d* and stem *d'*, connected 80 to the plug *c* and passing through the mortise 3, as a means for imparting to the plug a partial rotation, so as to bring the recess filled with tooth-powder from its normal position into place at the narrow mortise 2, so that 85 the powder in the recess can be delivered through the mortise 2 onto the brush lengthwise of the body of bristles.

I prefer, as shown in the drawings, to extend the stem *d'* through the hollow plug *c* and 90 through the bottom of the recess and to surround the same with a helical spring 4 and to employ a plate *e* in the base of the recess, lying normally against the bottom of the same, the plate *e* and the stem *d'* being firmly connected together.

The portion of the mortise 3 at the upper end of the cylindrical top *b* is of a width to freely receive the stem *d'*, while the base of the mortise 3 nearest to the tooth-powder receptacle or box is made large enough to receive the head *d*, the office of the stem and plate in this connection being both as a means for turning the plug from the normal position

where the recess receives the tooth-powder into the position at the mortise 2, where the tooth-powder is delivered, and as a means for forcing out the powder by the longitudinal movement of the stem d' , effected by a pressure of the finger upon the head d and the simultaneous movement of the plate e toward the mouth of the recess and the mortise 2 in the top, so as to insure the delivery of the tooth-powder.

I claim as my invention—

1. A tooth-powder box comprising a receptacle for the powder, a cylindrical top with closed ends, there being an internal opening 15 at the union of the top and receptacle, the said top having a narrow axial mortise in one side and a transverse mortise in the other side, a plug fitting said cylindrical top and having a recess of a size to receive tooth-powder sufficient for one application, said recess being normally in line with the opening between the cylindrical top and the tooth-powder receptacle, a stem and head connected to the plug and passing through the transverse 25 mortise of the cylindrical top as a means for imparting a partial rotation to the plug to bring the recess therein to coincide with the mortise in the side of the cylindrical top through which the tooth-powder of the recess 30 is delivered upon the brush, substantially as set forth.

2. A tooth-powder box comprising a receptacle for the powder, a cylindrical top with closed ends, there being an internal opening 35 at the union of the top and receptacle, the said top having a narrow axial mortise in one side and a transverse mortise in the other side, a hollow plug fitting said cylindrical top

and having a recess of a size to receive tooth-powder sufficient for one application, said recess being normally in line with the opening between the cylindrical top and the tooth-powder receptacle, a stem passing through the transverse mortise of the cylindrical top and through the hollow plug into the recess 45 and having a head outside the cylindrical top, a spring around the stem and a plate within the recess secured to the end of the stem and lying normally against the bottom of the recess, substantially as and for the purposes set forth.

3. A tooth-powder box comprising a receptacle for the powder, a cylindrical top with closed ends, there being an internal opening 50 at the union of the top and receptacle, the said top having a narrow axial mortise in one side and a transverse mortise in the other side, a plug fitting said cylindrical top and having a recess of a size to receive tooth-powder sufficient for one application, said recess 55 being normally in line with the opening between the cylindrical top and the tooth-powder receptacle, a plate within the recess lying normally against the bottom of the recess, a means connected to said plate for projecting 60 the same to deliver the tooth-powder from the recess and a means for turning the plug to bring the recess into line with the narrow axial mortise, substantially as and for the purposes set forth.

Signed by me this 7th day of July, 1899.

IRAD HAWLEY.
